US00D941457S

(12) **United States Design Patent** (10) **Patent No.:** **US D941,457 S**
Adams et al. (45) **Date of Patent:** **** Jan. 18, 2022**

(54) **DIETARY SUPPLEMENT**

(71) Applicant: **Nutramax Laboratories, Inc.**,
 Lancaster, SC (US)

(72) Inventors: **Brian Adams**, Lancaster, SC (US);
David Griffin, Forest Hill, MD (US);
Hubert Ratkowski, Simpsonville, SC (US)

(73) Assignee: **Nutramax Laboratories, Inc.**,
 Lancaster, SC (US)

(**) Term: **15 Years**

(21) Appl. No.: **29/730,685**

(22) Filed: **Apr. 7, 2020**

(51) **LOC (13) Cl.** **28-01**

(52) **U.S. Cl.** **USPC 24/103; D1/127**

CLAIM

The ornamental design for a dietary supplement, as shown and described.

DESCRIPTION

FIG. 1 is a top perspective view of a dietary supplement according to our new design;

FIG. 2 is a bottom perspective view thereof;

FIG. 3 is a side view thereof;

FIG. 4 is a top view thereof; and,

FIG. 5 is a bottom view thereof.

The broken line depictions form no part of the claimed design.
